US00D781255S

(12) **United States Design Patent** (10) Patent No.: **US D781,255 S**
(45) Date of Patent: **** Mar. 14, 2017**

(54) **LIGHT EMITTING DIODE**

(71) Applicants: **CITIZEN ELECTRONICS CO., LTD.**, Fujiyoshida-shi, Yamanashi (JP); **CITIZEN WATCH CO., LTD.**, Tokyo (JP)

(72) Inventor: **Shingo Kuriki**, Fujiyoshida (JP)

(73) Assignees: **Citizen Electronics Co., Ltd.**, Yamanashi (JP); **Citizen Watch Co., Ltd.**, Tokyo (JP)

(**) Term: **15 Years**

(21) Appl. No.: **29/553,232**

(22) Filed: **Jan. 29, 2016**

Entire patent prosecution history of U.S. Appl. No. 29/511,710, filed, Dec. 12, 2014, entitled, "Light Emitting Diode."

Primary Examiner — Selina Sikder

(74) *Attorney, Agent, or Firm* — RatnerPrestia

(57) **CLAIM**

The ornamental design for a light emitting diode, as shown and described.

DESCRIPTION

FIG. 1 is a perspective view of a light emitting diode;
FIG. 2 is a top plan view thereof;

FIG. 3 is a front view thereof;

FIG. 4 is a rear view thereof;

FIG. 5 is a left side elevational view thereof;

FIG. 6 is a right side elevational view thereof; and,

FIG. 7 is a bottom plan view thereof.

The broken lines shown in the drawings are for illustrative purposes only and form no part of the claimed design.

1 Claim, 5 Drawing Sheets
